DUMPING DEVICE FOR MILK CANS

Harold M. Kendall, Potsdam, N. Y.

Application February 8, 1949, Serial No. 75,129

12 Claims. (Cl. 214—1)

1

This invention relates to a dumping device for cans and is concerned more especially with an improved device for conveniently emptying returned milk cans prior to the washing and sterilizing operations which condition the cans for subsequent re-use.

One of the commonly employed practices in some localities for dumping residual milk from cans returned to the dairy or processing plant is to invert the can to a 180 degree position over a receptacle and allow the residual milk within the can to drain into the receptacle. However, many municipal and State Boards of Health do not allow this type of dumping. Furthermore, where the 180 degree or "Western type" dumping is allowed a cumbersome grid structure is required to support the can being emptied and the operation is invariably accompanied by excessive splashing which militates against the maintenance of sanitary and hygienic conditions. The practice of hand-dumping milk cans is commonly employed also, but hand-dumping is a primitive and uneconomical procedure which makes smooth, continuous and rapid dumping impossible and which requires that the operator hold the can for the entire time that the milk is draining therefrom.

Accordingly it is a primary object of the invention to provide a dumping device which will eliminate excessive splash while allowing the cans to be emptied in a smooth and rapid manner at a predetermined angle of inclination.

Another object of the invention is the provision of a dumping device of the character indicated which is constructed and arranged in such a manner as to maintain a can in dumping position without requiring the constant attendance of an operator during the draining operation.

A further object of the invention is the provision of a dumping device of the character indicated which may be readily associated with the feed table of a can washer in such a manner that the can may be conveniently pushed to loading position after the draining operation for subsequent washing and conditioning prior to re-use.

Another object of the invention is the provision of a dumping device of the character indicated which may be readily associated with a conveyor system and a can washer, the device being interposed in the line of travel of the cans between the delivery end of the conveyor and the feed table of the can washer and the device being arranged and constructed in such a manner as to prevent slippage of the can during the tilting and drawing operation.

2

An additional object of the invention is the provision of a dumping device of the character indicated which may be easily installed at the delivery end of a can conveyor and which includes means actuated by the can-supporting and dumping arm for preventing access of additional cans to dumping position while a given can is being dumped, thereby providing ample space for the tilting and manipulation of the can at the dumping station and preventing injury to the operator.

The foregoing objects as well as additional objects and advantages of the invention will be readily apparent in the course of the following detailed description taken in connection with the accompanying drawings which illustrate preferred embodiments of the invention and wherein:

Fig. 1 is a front elevation of a dumping device incorporating the features of the invention, the device being shown in cooperative relation with a can conveyor and the hopper of a receptacle for the residual milk within the can; and

Fig. 2 is a perspective view of the dumping device mounted on the conveyor frame.

Fig. 3 is a view similar to Fig. 1 but in rear elevation, i. e. looking toward the device from the feed table of the can washer; and

Fig. 4 is a top plan view of the arrangement illustrated in Fig. 3.

Fig. 5 is an elevational view, partly in sections, of a unified form of dumping device associated with the delivery end of a roller-type can conveyor and illustrates stop-mechanism actuated by the can-supporting element of the device for preventing access of additional cans to the dumping station while the leading can is being tilted and dumped;

Fig. 6 is a view similar to Fig. 5, but including a portion of the drainage receptacle and the feed table of the can washer, and illustrates the partial tilting of the leading can and the partial depression of the can-supporting element of the device; and

Fig. 7 is a view similar to Fig. 6 but illustrating the final phase of the tilting operation with the leading can in draining position and the can-supporting element restored to normal elevated position, thereby also returning the stop mechanism to elevated position preventing further access of cans to the dumping until the preceding can has been tilted over the device.

The device of the invention is most advantageously employed in connection with a conveyor

for transporting the cans and a can washer for cleaning the emptied cans, the dumping device preferably being interposed in the line of travel of the cans between the end of the conveyor and the feed table of the can washer, the feed table 22 of which is shown fragmentarily in the drawing.

Referring first to Figs. 1-4 inclusive, the drawings illustrate a conveyor 10 of the roller type or of any other suitable construction for transporting the returned cans to the dumping device designated generally by reference numeral 11. Dumping device 11 preferably comprises a pair of parallel frame members 12 bent or curved at their top ends to define arcuate portions 12a which serve as a cradle for tilting cans to inclined position, as clearly shown in Fig. 1.

The can is tilted to some predetermined angle, for example 150 degrees, with respect to the vertical axis of the receiver 13 and residual milk within the can drains into said receiver through the hopper 14. The mouth of the tilted can is held by a support or bar 15 which is preferably, but not necessarily, fixed to the frame of the device. The angular inclination of the can is determined by a support or stop-bar 16 against which the body of the can abuts in the draining position of the can, said support being disposed to limit the tilting of the can beyond a predetermined inclination.

An important feature of the invention resides in the provision of an arrangement for maintaining the can in draining position, illustrated in full lines in Fig. 1, throughout the draining operation without requiring the constant attention of an operator. Thus while the can is draining, the operator is left free for loading the can cover in the cover chute of the can washer 22 or for other operations and may prepare to push the emptied can forward to loading position on the feed table of the can washer. This desirable effect may be conveniently accomplished by means of a can-supporting member or lever 17 pivoted at 18 between frame members 12 and projecting outwardly of arcuate portions 12a thereof to terminate in lateral extensions 19 for supporting the body of the can in the operative position of said lever, illustrated in full lines in Fig. 1. Lever 17 may be provided with a lower angular extension 17a to which a spring 20 may be secured for normally urging said lever to elevated operative position limited by stop member 21. Alternatively, a counterweight (not shown) may be substituted for spring 20 in order to accomplish the same result.

As the can is tilted over the cradle or arcuate portions 12a of the device, lever 17 is progressively depressed from the operative full line position of Fig. 1 until the can assumes its draining or fully tilted position, whereupon said lever returns to normal operative position maintaining the can in draining position.

The dumping device is most advantageously employed as part of a continuous system including a conveyor for the cans and a can washer, the device being interposed in the line of travel of the cans between the conveyor and the washer. Where this arrangement of the dumping device is employed, lower support-bar 15 and upper stop-bar 16 are preferably mounted on the can washer, as shown in Figs. 3 and 4, so that said lower support bar will maintain the can at the same level as the washer feed table 22 and stop-bar 16 is shaped in such a manner as to facilitate pushing the emptied can forward to loading posi-

tion on the washer. A guide bar 23 cooperates with stop-bar 16 to tilt the can to upright inverted position on feed table 22, as clearly shown in Fig. 4.

The design and arrangement of the present invention permits more draining time for the can and eliminates splash caused by conventional grids without requiring the constant attendance of an operator during the draining period. Further, it permits a smaller hopper to be employed on the drainage receptacle and eliminates the use of the special splash grids employed in conventional practice. The novel arrangement of the invention eliminates the need of expensive preconditioners thereby also conserving valuable space, since many health authorities require that separate rooms be provided where preconditioning equipment is employed.

Figs. 5, 6 and 7 illustrate a modified form of dumping device affixed to the delivery end of a conveyor 30 having the rollers 31 for transporting the cans to the dumping station. As in the initially described embodiment of the invention, the dumping device preferably comprises a pair of parallel frame members 32 bent or curved at their top ends to define arcuate portions 32a which serve as a cradle over which the cans may be tilted to inclined draining position, whereupon residual milk within the can flows into the drainage receptacle 13 through the hopper 14. The mouth of the can is retained in draining position by supporting members 15, in the form of bars or rails, which are preferably extended from the feed table of the can washer (not shown) on a level therewith, since the dumping device is most advantageously utilized by being interposed in the line of travel of cans between the conveyor 30 and a can washer for rapid and continuous dumping prior to washing and sterilizing the cans for subsequent re-use. The angle of inclination of the can is determined by the stop-member or bar 16 suitably secured to a standard 33.

The can-supporting member or lever 34 is pivoted at 29 between frame members 32 and is provided with a preferably L-shaped or right angled upper extension 34a projecting outwardly of cradle or arcuate portions 32a, said extension 34a serving not only to support the can as it is tilted over the cradle (see Fig. 6) but also for supporting the can in inclined draining position (see Fig. 7) as member 34 returns to its normal elevated position.

In order to prevent slippage of the can as it is being tilted and to provide easy registration of the mouth of the can in proper position against the lower supporting members 15, can-supporting member 34 is provided with a lower projection or ledge 35 which catches and retains the bottom of the can being tilted, as clearly shown in Fig. 6.

Can-supporting member 34 also controls the operation of an arrangement for preventing access of additional cans to the dumping station while the leading can is at the dumping station 65 waiting to be tilted over the cradle and this arrangement will now be described. A can stop 36 is mounted on conveyor 30 in a guide member 37 for up and down motion to alternately obstruct and clear the path of cans traveling toward the dumping station. The lower end of can stop 36 is pivoted at 38 to the stop lever 39 which is pivotally supported in any suitable manner intermediate its ends at 40, as by means of bracket 41 depending from the frame of the conveyor. The opposite 75 end of stop lever 39 is supported at 42 by an arm

43 pivotally secured at its upper end to can-supporting member 34 as at 44. The weight of lever 39 normally exerts a downward pull on member 34 through arm 43 and serves to maintain member 34 as well as can stop 36 in elevated position.

In order to initiate the dumping operation when there are no cans in dumping position, it is necessary for the operator to either momentarily depress the can-supporting member 34 or elevate the free forward end of stop lever 39. This lowers the can stop 36 and allows a can to move forward into dumping position after which said can stop and member 34 are automatically restored to normal elevated position by the balance of the system, as shown in Fig. 5. As the can being dumped is tilted over arcuate cradle 32a, the can-supporting member 34 is progressively depressed and the bottom of the can is firmly supported against the lower projecting ledge 35. In order to clarify the successive stages of the dumping operation as shown in Figs. 5-7, the first three cans on the conveyor are designated A, B and C.

As can A is tilted in the manner described, can-supporting member 34 is depressed, arm 43 is raised and bears against lever 39 swinging it in a counterclockwise direction about its pivot 40, whereupon can stop 36 is lowered allowing can B to advance to the dumping station, as shown in Fig. 6. When the can has been completely tilted to draining position, as shown in Fig. 7, the weight of lever 39 restores can-supporting member 34 to normal elevated position with its upper extension 34a supporting the can. Simultaneously with the elevation of member 34 the can stop 36 is also raised, preventing advancement of can C to dumping position until can B is tilted. This arrangement contributes to a smooth dumping operation, provides ample space for tipping the can at the dumping station without interference by oncoming cans and eliminates the possibility of injury to the operator.

As a further precautionary measure fingers 45 may be pivotally mounted on a counterweighted arm 46 for the purpose of reducing the speed and impact of the cans arriving at the dumping station so as to preclude any possibility of spilling or splashing of milk.

Since certain modifications may be made in the device of the present invention without departing from the scope thereof, it is intended that all matter contained in the foregoing description and shown in the accompanying drawings be interpreted merely as illustrative and not in a limiting sense.

I claim:

1. A dumping device for emptying milk cans, comprising a pair of frame members defining arcuate portions to permit tilting a can thereover, a lower support member retaining the mouth of the can in inclined draining position, a can-supporting element swingably mounted between the arcuate portions of said frame members and projecting outwardly therefrom, said element being normally urged to operative elevated position maintaining the can in draining position and being compressible into inoperative position while the can is being tilted to draining position.

2. A dumping device for emptying milk cans, comprising a pair of frame members defining arcuate portions to permit tilting a can thereover, a lower support member retaining the mouth of the can in inclined draining position, a stop member limiting the angle of inclination of the can to a predetermined inclination, a can-supporting element swingably mounted between the arcuate

portions of said frame members and projecting outwardly therefrom, said element being compressible to inoperative position while the can is being tilted to inclined draining position, and means associated with said element and normally urging said element into elevated operative position for maintaining the can in inclined draining position.

3. A dumping device for emptying milk cans, comprising a pair of frame members defining arcuate portions to permit tilting a can thereover, a lower support member retaining the mouth of the can in inclined draining position, a stop member limiting the angle of inclination of the can to a predetermined inclination, a can-supporting element swingably mounted between the arcuate portions of said frame members and projecting outwardly therefrom, said element being compressible to inoperative position while the can is being tilted to inclined position, and spring means associated with said element and normally urging said element into elevated operative position for maintaining the can in inclined draining position.

4. In combination with a can washer having a feed table, a dumping device for emptying milk cans, said device comprising a pair of frame members defining arcuate portions to permit tilting a can thereover, a lower support member retaining the mouth of the can in inclined draining position at the level of the feed table of the can washer, a stop member limiting the angle of inclination of the can to a predetermined inclination, a can-supporting element swingably mounted between the arcuate portions of said frame members and projecting outwardly therefrom, said element being compressible to inoperative position while the can is being tilted to inclined draining position, and means associated with said element and normally urging said element into elevated operative position for maintaining the can in inclined draining position.

5. In combination with a can washer having a feed table, a dumping device for emptying milk cans, said device comprising a pair of frame members defining arcuate portions to permit tilting a can thereover, a lower support carried by said can washer for retaining the mouth of the can in inclined draining position at the level of the feed table, a stop-guide member carried by said can washer for limiting the angle of inclination of the can to a predetermined inclination, whereby to facilitate pushing the can to loading position on said feed table, a can supporting element swingably mounted between the arcuate portions of said frame members and projecting outwardly therefrom, said element being compressible to inoperative position while the can is being tilted to inclined draining position, and means associated with said element and normally urging said element into elevated operative position for maintaining the can in inclined draining position.

6. A dumping device for emptying milk cans, comprising a pair of frame members defining arcuate portions to permit tilting a can thereover, a lower support member retaining the mouth of the can in inclined draining position, a stop member limiting the angle of inclination of the can to a predetermined inclination, a can-supporting element swingably mounted between the arcuate portions of said frame members and projecting outwardly therefrom, said element compressible to inoperative position while the can is being tilted to inclined draining position, said element having a lower angular extension, fixed stop means arranged to abut said angular extension in the elevated operative position of said element,

and means associated with said element and urging said element into abutment against said stop means for maintaining the can in inclined draining position.

7. In combination with a can washer having a feed table, a dumping device for emptying milk cans, said device comprising a pair of frame members defining arcuate portions to permit tilting a can thereover, a lower support member retaining the mouth of the can in inclined draining position at the level of the feed table of the can washer, a stop member limiting the angle of inclination of the can to a predetermined inclination, a can-supporting element swingably mounted between the arcuate portions of said frame members and projecting outwardly therefrom, said element being depressible to inoperative position while the can is being tilted to inclined draining position, said element having a lower angular extension, fixed stop means arranged to abut said angular extension in the elevated operative position of said element, and means associated with said element and urging said element into abutment against said stop means for maintaining the can in inclined draining position.

8. A dumping device for emptying milk cans, comprising a pair of frame members defining arcuate portions to permit tilting a can thereover, a lower support member retaining the mouth of the can in inclined draining position, a can-supporting element swingably mounted between the arcuate portions of said frame members and projecting outwardly therefrom, said element having a rearwardly projecting ledge supporting the can against slippage during the tilting operation, said element being normally urged to operative elevated position maintaining the can in draining position and being depressible into inoperative position while the can is being tilted to draining position.

9. A dumping device for emptying milk cans, comprising a pair of frame members defining arcuate portions to permit tilting a can thereover, a lower support member retaining the mouth of the can in inclined draining position, a guide member limiting the angle of inclination of the can to a predetermined inclination, a can-supporting element swingably mounted between the arcuate portions of said frame members and projecting outwardly therefrom, said element having a rearwardly projecting ledge supporting the can against slippage during the tilting operation, said element being depressible to inoperative position while the can is being tilted to inclined draining position, and means associated with said element and normally urging said element into elevated operative position for maintaining the can in inclined draining position.

10. In combination with conveyor means for transporting cans to a dumping station, a dumping device for tilting and emptying said cans comprising a pair of frame members defining arcuate portions to permit tilting a can thereover, a lower support member retaining the mouth of the can in inclined draining position, a guide member limiting the angle of inclination of the can to a predetermined inclination, a can-supporting element swingably mounted between the arcuate portions of said frame members and projecting outwardly therefrom, said element hav-

ing a rearwardly projecting ledge supporting the can against slippage during the tilting operation, said element being normally urged to operative position maintaining the can in draining position and being depressible into inoperative position while the can is being tilted to draining position, and stop means carried by said conveyor means and cooperating with said can-supporting element to allow access of oncoming cans to the dumping station only while a can is being tilted to dumping position over said element.

11. In combination with conveyor means for transporting cans to a dumping station, a dumping device for tilting and emptying said cans comprising a pair of frame members defining arcuate portions to permit tilting a can thereover, a lower support member retaining the mouth of the can in inclined draining position, a guide member limiting the angle of inclination of the can to a predetermined inclination, a can-supporting element swingably mounted between the arcuate portions of said frame members and projecting outwardly therefrom, said element having a rearwardly projecting ledge supporting the can against slippage during the tilting operation, said element being normally urged to operative position maintaining the can in draining position and being depressible into inoperative position while the can is being tilted to draining position, and depressible stop means carried by said conveyor means and interposed in the path of travel of the cans to the dumping station, said stop means being operatively connected with said can-supporting element, whereby to depress said stop means and allow access of oncoming cans to the dumping station upon depression of said element by tilting a can thereover.

12. In combination with conveyor means for transporting cans to a dumping station, a dumping device for tilting and emptying said cans comprising a pair of frame members defining arcuate portions to permit tilting a can thereover, a lower support member retaining the mouth of the can in inclined draining position, a guide member limiting the angle of inclination of the can to a predetermined inclination, a can-supporting element swingably mounted between the arcuate portions of said frame members and projecting outwardly therefrom, said element having a rearwardly projecting ledge supporting the can against slippage during the tilting operation, said element being normally urged to operative position maintaining the can in draining position and being depressible into inoperative position while the can is being tilted to draining position, depressible stop means carried by said conveyor means and interposed in the path of travel of the cans to the dumping station, a lever pivotally mounted intermediate its ends, the free end of said stop means being pivoted to one end of said lever, and an arm pivotally secured to said can-supporting element and supporting the free end of said lever, whereby depression of said can-supporting element upon tilting a can thereover is accompanied by depression of said stop means to allow access of oncoming cans to the dumping station.

HAROLD M. KENDALL.
